CLAIM

The ornamental design for a docking station as shown and described.

DESCRIPTION

FIG. 1 is a front, right and top perspective view of a docking station showing our design.

FIG. 2 is a rear, left and bottom perspective view thereof.

FIG. 3 is a front elevation view thereof.

FIG. 4 is a rear elevation view thereof.

FIG. 5 is a left-side elevation view thereof.

FIG. 6 is a right-side elevation view thereof.

FIG. 7 is a top plan view thereof.

FIG. 8 is a bottom plan view thereof.

FIG. 9 is an enlarged view of portion 9 shown in FIG. 1; and, FIG. 10 is an enlarged view of portion 10 shown in FIG. 5. The broken lines are included for the purposes of illustrating portions of the docking station that form no part of the claimed design.

1 Claim, 10 Drawing Sheets
